MODULATING SYSTEM

Glen S. Whidden, Charlotte, Mich., assignor to
 Wilcox-Gay Corporation, Charlotte, Mich., a
 corporation of Michigan

Application March 11, 1947, Serial No. 733,755

8 Claims. (Cl. 179—171.5)

1

My invention relates to a modulation system, and particularly to a system for improved linearity in the modulated output of a tetrode, class C, amplifier.

The process of modulation of a class C amplifier consists in varying the plate voltage, and hence the plate current, in accordance with the modulating signal. For example, with 100% modulation by a sinusoidal voltage, the plate voltage is varied from its normal unmodulated value to twice its normal value at the positive peak of the modulating wave, back to normal, then to zero and back to the normal value. This results in a corresponding variation in the plate current and the production of a modulated wave, and is accomplished readily in triode amplifiers by inserting the source of modulating voltage in series with the plate voltage supply.

The primary characteristic of a screen grid tube which differentiates it from a triode tube is the dependence of the plate current upon the screen grid voltage. That is, plate current is substantially independent of the plate voltage, and almost entirely dependent upon the screen voltage.

Therefore, when using a screen grid tube as a class C modulated amplifier, it is necessary to modulate the screen voltage in addition to the plate voltage in accordance with the modulating signal.

In a well known circuit arrangement, this has been accomplished by providing two windings on the secondary of the output transformer of the modulating amplifier. The first winding supplies modulating voltage for the plate circuit and the second winding supplies modulating voltage to the screen grid.

Another circuit arrangement in use supplies the screen grid voltage from the plate voltage supply through a voltage dropping resistor connected to a part of the plate circuit where the modulating voltage exists, as, for example, the high side of the modulating transformer secondary.

Both of these, as well as other existing circuit arrangements result in production of non-linearity of the modulation characteristic, and consequent distortion of the negative peaks of the modulated signal when high percentage modulation is attempted.

I have discovered that this non-linearity is due to a characteristic of the screen grid tube; that a screen grid persistence current continues to flow at and near the negative peak of the modulating voltage; that is, when the screen grid

2

applied voltage is at or near zero. This current is due to the space charge effects prevalent within the tube, or the well known diode, or Edison effect, or a combination of both, and the reactive voltage drop in the cathode to ground wiring.

I have discovered means, as embodied in my invention, for introducing a voltage which counteracts the effects of this screen grid persistence current and improves the linearity of the modulation characteristic.

It is therefore an object of my invention to provide means for modulating screen grid tubes.

A further object of my invention is to provide means for 100% modulation of screen grid tubes.

Still another object of my invention is to provide means for improving the linearity of modulation of screen grid tubes.

These and other objects of my invention will become apparent from the following description in which

Figure 1 shows one embodiment of my invention.

Figure 2 shows screen grid and plate voltage and current curves for various conditions of operation.

Figure 3 shows a simplification of the embodiment of my invention shown in Figure 1.

In Figure 1, I have shown a source of radio frequency voltage 1 connected between the grid and cathode of a tetrode amplifier 2 in series with bias battery 3 which adjusts said amplifier for class C operation. The plate of amplifier 2 is connected to tuned circuit 4 which is adjusted to resonate with the frequency of source 1. A load 15, which may be another amplifier, an antenna or other applicable device, is coupled to tuned circuit 4 and extracts power thereby from the plate circuit by means of coupling coil 14. Plate voltage is supplied through the inductor 16 from battery 12, a source of high voltage.

The screen grid 18 is connected to the source of high voltage by two paths. The first comprises resistor 7 connected to inductor 16 at junction 13 and resistor 8, and the second comprises resistors 9, 10 and 11.

Modulation is applied by voltage induced in inductor 16 which is coupled through capacitor 17 and transformer 5 to modulator 6.

In Figure 2, dashed line 19 represents the unmodulated plate voltage E_p applied to the plate of tube 2 due to battery 12, and curve 21 represents the variation of voltage with respect to time for one cycle of the modulating frequency and for 100% modulation. Dashed line 20 represents the screen voltage E_{sg} for no modulation. Curve 22

represents the variation in screen voltage as in the case of curve 21.

Curve 23 represents the variation of plate current with 100% modulation, and curve 26 represents the variation of screen current with modulation.

In Figure 3, I have shown a simplification of my circuit in Figure 1. In Figure 3 a source 25 of radio frequency voltage E_0 is impressed on the input of a tetrode amplifier 35 having an equivalent load resistance 27 which amplifier 35 would see when connected to a loaded tuned circuit. Resistors 28 and 29 in series comprise a voltage divider for supplying both direct current and modulating voltage to the screen of 35, which is also connected to a resistance 33 and through this resistance to a power supply bleeder resistor 31. A source of modulating voltage 32 and plate supply battery 33 complete the circuit.

In order to clarify the ideas embodied in my invention, consider conditions when resistor 30 of Figure 3 is removed. Referring to Figure 3, voltage is then supplied to the screen grid 34 through the voltage divider action of resistor 28 and 29 only. If now, referring to Figure 2, a 100% modulating signal is supplied from modulator 32 to the plate and screen of tube 35, the voltage as shown by curve 21 of Figure 2 impressed on the plate will vary from its normal value shown by line 19 to twice that value on the positive half cycle, and then to zero and back to normal on the negative half cycle during each cycle of the modulating signal.

Similarly, the impressed screen voltage shown in curve 22 will vary from normal value shown by line 20 to twice normal on the positive half cycle, and then to zero and back to normal on the negative half cycle. Due, however, to the aforementioned effects and rectification of R. F. voltage E_0 , a persistence current shown by part 27 of curve 26 will continue to flow to the screen grid through resistor 29 from c to s, even when the screen voltage is at or near zero.

This current in combination with various others has certain undesirable effects, as follows: Current I_2 due to impressed voltage E_2 flows through resistor 28 and through resistor 29 from s to c. Current I_3 due to battery 33 flows through resistor 30 and resistor 29 from s to c.

Thus, the resultant current I_4 flowing in resistor 29 is due to the algebraic sum of I_1 , I_2 and I_3 . Now, at the point a in the negative half cycle (negative modulation peak), E_2 is zero and hence I_2 is zero. Furthermore, it has been postulated that resistor 30 is removed from the circuit and hence I_3 is zero. Thus, I_4 is comprised only of I_1 , and E_4 due to the potential drop in resistor 29 is in the direction of I_1 so that s is negative with respect to c. Hence a negative bias results, cutting off or reducing the plate current flow in tube 35 at and near the negative modulation peak. This is illustrated by part 24 of curve 23 in Figure 2. Part 27 of curve 26 represents the current I_1 discussed herein. Thus, as a result of the said persistence, current will flow over a considerable portion of the modulating cycle, introducing serious distortion of the modulated wave.

If now resistor 30 is replaced in Figure 3, and so adjusted that at the negative peak of the modulating cycle, current I_3 which flows in opposition to current I_1 is made equal to I_1 , then current I_4 will be zero at the negative peak since current I_2 will also be zero. Thus voltage E_4

will be zero, and no undesirable bias will be applied to the screen 34 of tube 35. Hence at all other points in the modulating voltage cycle E_4 will be $E_2 - E_5$, and since E_5 can never exceed E_2 the screen voltage will never be negative.

Thus by introduction of resistor 30 in my modulating circuit, I have produced a novel and unusual way of reducing distortion in screen grid modulated amplifiers.

- 10 Referring now to Figure 1, it is clear that this is substantially the same circuit as shown in Figure 3, except that it includes the practical elements necessary for normal operation of any vacuum tube amplifier, and that I have substituted for resistors 30 and 31 of Figure 3 the resistor combination 9, 10 and 11. This substitution in no way affects the operation of the circuit, herein described, but is well known to be more desirable for purposes of stability.
- 15 20 Since many variations and applications of the ideas embodied in my invention will be apparent to those skilled in the art, I prefer to have my invention described by the following claims.

I claim:

- 25 1. In an amplifier circuit, an amplifier tube having at least four elements including a screen grid and a plate, means including circuit connections to said plate for applying voltage from said plate circuit to said screen grid, and means 30 including circuit connections for counteracting the effect of screen grid persistence current.
2. In an amplifier circuit, an amplifier tube having a screen grid and a plate, means including circuit connections to said plate for modulating the plate voltage, means for applying voltage from said plate circuit to said screen grid, and means including circuit connections for counteracting the effect of screen grid persistence current.
3. In an amplifier circuit, an amplifier tube having a screen grid and a plate, means including circuit connections to said plate for modulating the plate voltage, means for applying voltage from said plate circuit to said screen grid, 45 and means including circuit connections for counteracting the effect of screen grid persistence current, said means comprising one or more resistors connected to said circuit for applying voltage to said screen grid.
4. In an amplifier circuit, an amplifier tube having a cathode, a grid, a screen grid, and a plate, a source of radio frequency connected between said grid and cathode, a biasing means in series with said source, a load, a tuned circuit 55 connecting said plate to said load, a source of plate voltage, an inductor connecting said voltage source to said plate, a resistor connecting one terminal of said voltage source through said inductor to said screen grid, a second resistor 60 connecting the opposite terminal of said voltage source to said screen grid, said opposite terminal being connected to said cathode, a pair of resistors connected across said voltage source, a third resistor extending from the mid connections 65 of said pair of resistors to said screen grid, a source of modulating current connected to said plate circuit through said inductor.
5. In an amplifier circuit, an amplifier tube having a cathode, a grid, a screen grid, and a plate, a source of radio frequency connected between said grid and cathode, a load, a tuned circuit connecting said plate to said load, a source of plate voltage, an inductor connecting said voltage source to said plate, a source of modulating current connected to said plate circuit

through said inductor, and means including a voltage divider circuit connecting said screen grid to said plate circuit and source of voltage for applying a compensating voltage to said screen grid due to screen grid persistence current.

6. In an amplifier circuit, an amplifier tube having a cathode, a grid, a screen grid and a plate, a source of radio frequency connected between said grid and cathode, a load, a tuned circuit connecting said plate to said load, a source of plate voltage, an inductor connecting said voltage source to said plate, a source of modulating current connected to said plate circuit through said inductor, and means including a voltage divider circuit connecting said screen grid to said plate circuit and source of voltage for developing a positive voltage to said screen grid during the negative half cycle which equals the negative voltage developed due to screen grid persistence current.

7. The method of operating an amplifier tube which comprises modulating the plate voltage in accordance with predetermined signals, modulating the screen grid in accordance with said

predetermined signals, and supplying a positive voltage to the screen grid during the negative half cycle which equals the negative voltage developed due to screen grid persistence current.

- 5 8. In an amplifier having a tube comprising a plate and a screen grid, means including circuit connections for plate modulating the plate voltage in accordance with predetermined signals, means for modulating the screen grid voltage in accordance with predetermined signals, and means for supplying a positive voltage to the screen grid during the negative half cycle which equals the negative voltage developed due to screen grid persistence current.
